UNITED STATES PATENT OFFICE.

JOHN S. TOWNSEND, OF HARVEY, ILLINOIS, ASSIGNOR TO WHITING CORPORATION,
OF HARVEY, ILLINOIS, A CORPORATION OF ILLINOIS.

LADLE-TURNING MECHANISM.

Application filed January 27, 1923. Serial No. 615,211.

To all whom it may concern:

Be it known that I, JOHN S. TOWNSEND, a citizen of the United States, residing at Harvey, in the county of Cook and State of Illinois, have invented a certain new and useful Improvement in Ladle-Turning Mechanism, of which the following is a specification.

This invention relates to mechanism for turning ladles used in foundries, furnaces and the like containing more or less large bodies of molten metal, sometimes thirty tons or more, wherein because of the danger of spilling molten metal, very positive powerful machinery is required. In general terms, the invention is an improvement upon the devices of prior Patents 1,323,137 to Whiting and Townsend and 1,357,599 to Townsend.

20 The objects of the invention are to improve the mechanisms and method of constructing and assembling the devices of said prior patents, thereby reducing the original cost and increasing the efficiency and safety 25 of the device and to provide an automatic oiling system for the mechanism which reduces the sources of oil supply from seven or eight to two, thus materially increasing the satisfactory operation of the device.

30 The invention consists in mechanism capable of attaining the foregoing objects; which can be easily and comparatively cheaply made; which is satisfactory in operation and is not readily liable to get out 35 of order. More particularly, the invention consists in numerous features and details of construction which will be hereafter more fully set forth in the specification and claims.

40 Referring to the drawings in which like numerals designate the same parts throughout the several views:

Figure 1 is a small side elevation of a complete ladle equipped with the mechanism 45 of this invention.

Figure 2 is a larger side elevation and Figure 3 a corresponding end elevation, certain parts being broken away, of mechanism illustrating this invention in its preferred form.

Figure 4 is a plan view of the device of Figures 2 and 3, taken on the line 4-4 of Figure 5.

55 Figure 5 is a vertical sectional detail view on the line 5-5 of Figure 4.

Figure 6 is a transverse end view, largely in section, taken on the line 6-6 of Figure 4.

Figure 7 is a vertical, sectional detail view on the line 7-7 of Figure 5. 60

Figure 8 is a true plan view of the top of the case taken somewhat above the line 4-4 of Figure 5.

The ladle 12 adapted to carry a large quantity of molten metal appearing in Figure 1 has conveniently protruding from its sides trunnions 14 and 16 journaled in a conventional form of bail 18 adapted to be suspended in conventional manner from the traveling crane or other carrier device movable about a foundry. As in said prior patents, the trunnion 16 has rigidly attached to it by any suitable means as, for instance, the key 20, a large gear wheel 22, 65 driven by a worm 24, operated in any convenient manner, as, for instance, by the manual manipulation of an associated hand wheel 26, the gearing mechanism being enclosed within some sort of a case held by the bail 18 in such a manner that the bail and case can expand vertically as shown in the drawings with reference to each other but the case and included worm mechanism cannot rotate on the trunnion 16. 70

In the improved construction of this invention, the case is greatly improved by including in it two parallel side frames 28 and 30 of generally triangular construction, usually, but not necessarily, castings, located on opposite sides of gear wheel 22 75 terminating at their downwardly pointed ends in bearings 32, journaling the trunnion 16. These parallel frames 28 and 30 support a detachable case 34 fitting over and enclosing the worm 24, its shaft 36 and spiral gear 38 driven by it. The case 34 is secured to suitably disposed horizontal flanges on the frame members 28 and 30 by any suitable means as, for instance, the bolts 40. Case 34 is made longer than the 80 top edges of the members 28 and 30 and carries beyond them the depending shaft receptacle 42 in which is journaled shaft 44 carrying inside of shaft receptacle 42 the worm 46 meshing with spiral gear 38 and carrying outside of the case the hand wheel 26, heretofore referred to, or any other convenient mechanism not entering into this 85 invention for rotating the gearing described and, consequently, through the wheel 22 the 90

95 In the improved construction of this invention, the case is greatly improved by including in it two parallel side frames 28 and 30 of generally triangular construction, usually, but not necessarily, castings, located on opposite sides of gear wheel 22 terminating at their downwardly pointed ends in bearings 32, journaling the trunnion 16. These parallel frames 28 and 30 support a detachable case 34 fitting over and enclosing the worm 24, its shaft 36 and spiral gear 38 driven by it. The case 34 is secured to suitably disposed horizontal flanges on the frame members 28 and 30 by any suitable means as, for instance, the bolts 40. Case 34 is made longer than the top edges of the members 28 and 30 and carries beyond them the depending shaft receptacle 42 in which is journaled shaft 44 carrying inside of shaft receptacle 42 the worm 46 meshing with spiral gear 38 and carrying outside of the case the hand wheel 26, heretofore referred to, or any other convenient mechanism not entering into this invention for rotating the gearing described and, consequently, through the wheel 22 the 100

105

110

ladle. The shaft receptacle 42 is rendered accessible through an end perforation 48 closed by a plate 50, detachably secured in position by any suitable means as, for instance, the screws or bolts 52.

Obviously, the members 30, 32 and 34 only enclose a segment of the gear wheel 22. The portion of the wheel not covered by the parts named is preferably but not necessarily enclosed in any conventional form of case member 53, usually but not necessarily of sheet iron, suitably attached to flanges on the members 28 and 30 by any suitable means as, for instance, the screws 54 entering holes 56 provided for them and by bolts 58 and 60 entering the case member 34 and a flange on member 42 as shown.

The mechanism thus far described has the distinct advantage that side frames 28-30 support case member 34 from the trunnion 16 on two separated, spaced bearings 32, with the result that worm 24 is held in accurate alignment with worm gear 22, thus increasing the efficiency of the worm gearing devices which are, as is well understood in the art, subject to great deterioration in efficiency, if the parts are not maintained in proper relationship. Again, by constructing the three parts 28, 30 and 34 as described, much more ready repair and replacement can be carried on should occasion require them than with the structures of said prior patents.

In order to provide proper automatic lubrication of the mechanism described, case 34 is provided with two upwardly extending rectangular oil boxes 62 and 64, the former being provided on the side nearest the bail 18 with a U-shaped notch 66 entered by a horizontally projecting arm 68 on a U-shaped block 70 embracing the bail 18 and detachably secured in place by any suitable means as, for instance, the bolts 72 provided for the purpose. This block 70 is preferably cored out, as shown at 74, Figures 4 and 6, so as to make the walls of substantially uniform thickness in all directions, thereby doing away with the danger of breakage adjacent to the corners of the bail were it made solid at 74. The block 70 is cut away at the top and bottom of the portion 68 in curved lines 76 conforming to the curvature of that portion of the case 34 which directly encloses the worm 24. In practice, the member 70 is shipped separately from the bail 18 and the curves 76 are provided so that the constructor at the final works where the device is to be used can apply members 68-70 either side up without getting into trouble.

Lug 68 fits closely but not tight between the walls of the recess 66 and has sufficient clearance with reference to the outside of case cover 34 so that it cannot even touch cover 34 should heat distort bail 18 or ladle

bowl 12; in other words, bail 18 or the ladle 12 can expand freely without pulling or pushing on the case 34 and, consequently, upon the gearing contained in the case to thus destroy the successful operation of the worm gear mechanism.

The oil chambers 62 and 64, heretofore referred to, are respectively closed by covers 80 and 82, secured in place by any suitable means—that shown in the drawings comprising in each case a pivotal bearing 84 at one corner and a set screw 86 on co-operating open ended slot 88 at the other corner, the slot being formed on the arc of a circle drawn from the adjacent pivot 84 so that the respective covers can be rotated in a horizontal plane sufficiently so that the respective oil boxes can be filled with waste 90 loaded with heavy oil.

In the bottom of oil box 62 are five oil holes: 91-92-93-94 and 95, while in the bottom of oil box 64 are four oil holes 96-97-98 and 99.

Oil hole 91 is, as shown, located immediately adjacent to the inside wall of member 28 and adjacent to a rib 100 thereon down which oil from said hole 91 travels to an oil receptacle 102 in the adjacent hub 32 from which the oil passes through a hole 104 to the outer end of trunnion 16. Similarly, oil hole 95 is immediately adjacent to the inner wall of case member 30 and a rib 106 thereon down which the oil travels to an oil chamber 108 from which it goes through hole 110 to the inner end of trunnion 16. Oil hole 92 delivers directly to a central bearing 112 provided for shaft 36 inside of case 34. Oil hole 93 delivers oil directly to the worm 24, while oil hole 94 delivers oil to the downwardly inclined passage 114 leading to a bearing 116 for the outer end of shaft 36, in end plate 118, attached to the case member 34 by any suitable means as, for instance, the bolts 120.

In similar manner, oil holes 96 and 99 deliver oil to opposite inside faces of case 34 down which the oil flows to oil cups 120 and 122 in the shaft retaining device 42 from which the oil passes through the ports shown in Figure 7 to the opposite end bearings of shaft 44.

Oil hole 97 delivers directly to the top of spiral gear 38 and consequently to the worm 46, while oil hole 98 delivers, as shown in Figure 5, directly to a bearing 124 which supports shaft 36, immediately adjacent to spiral gear 38.

In order to prevent all the oil in waste 90 in boxes 62 and 64 running out of the oil holes as 91, 95, 96 and 99, which are below the other oil holes in the respective boxes, oil boxes are preferably divided into separate compartments by suitable partitions 126-128-130 and 132.

In the operation of the device, the op-

erator charges the oil chambers 62 and 64 with waste 90, loaded with very heavy slow flowing oil and closes the covers 80 and 82, with the result that the oil flows very slowly 5 out of the waste through the respective oil holes to the various gears and bearings with the practical result that it is only necessary to pay attention to the lubrication of the device once a month or so instead of every day 10 as has heretofore been required where a multiplicity of oil cups, grease cups, etc., are independently applied to each of the separate points requiring lubrication.

By the use of the entire invention, automatically lubricated mechanism is obtained 15 in which the delicate worm gear is rigidly, yet detachably and demountably secured in proper operative position.

As the drawings are clear, it is hardly 20 necessary to state that the case is held on the trunnion 16 by thrust bearing 134, and that shaft 44 is positioned by thrust bearing 136.

In actual practice, mechanism constructed 25 in accordance with the foregoing drawings and description, has been successfully operated with very much greater efficiency and economy than is possible with the prior devices of the art.

Having thus described my invention, 30 what I claim as new and desire to secure by Letters Patent is:

1. The combination with a ladle having a trunnion extending therefrom journaled in 35 a supporting bail; of a worm wheel affixed to said trunnion, mechanism for rotating said worm wheel held against movement circumferentially of said worm wheel by said bail, means for supporting said worm 40 wheel rotating mechanism from said truncated one to each side of said worm wheel,

said frame members being rotatably journaled on said trunnion, a housing for said worm wheel rotating mechanism rigidly connecting said frame members together, an 45 oil reservoir in said housing, and a rib on each frame member extending from a point adjacent to said oil reservoir to a point adjacent to said trunnion and to which oil from said reservoir is delivered whereby it 50 flows to said trunnion.

2. The combination with a ladle having a trunnion extending therefrom journaled in a supporting bail; of a worm wheel affixed to said trunnion, mechanism for rotating said worm wheel held against movement circumferentially of said worm wheel by said bail and including a shaft, bearings in which said shaft is journaled and a worm on said shaft meshing with said worm wheel, 55 a pair of frame members journaled on said trunnion, a housing for said worm and said shaft carried by said frame members, an oil reservoir in said housing, partitions dividing said oil reservoir into separate compartments, one of said compartments having passages leading therefrom to said shaft bearings and to said worm, a rib on each frame member extending from a point adjacent to said oil reservoir to an oil pocket 60 65 70 adjacent to said trunnion, the other compartments having passages leading to said ribs, respectively, whereby oil is delivered to the latter so as to adhere thereto by capillary attraction and flow to said oil 75 pockets, said frame members having passages leading from said oil pockets to said trunnion.

In witness whereof, I have hereunto subscribed my name.

JOHN S. TOWNSEND.

Certificate of Correction.

It is hereby certified that in Letters Patent No. 1,550,004, granted August 18, 1925, upon the application of John S. Townsend, of Harvey, Illinois, for an improvement in "Ladle-Turning Mechanism," an error appears in the printed specification requiring correction as follows: Page 3, lines 40 and 41, claim 1, strike out the word "truncated" and insert instead *trunnion including a pair of frame members located*; and that the said Letters Patent should be read with this correction therein that the same may conform to the record of the case in the Patent Office.

Signed and sealed this 13th day of October, A. D. 1925.

[SEAL.]

KARL FENNING,
Acting Commissioner of Patents.
